UNITED STATES PATENT OFFICE.

HERMENEGILDE CARRIER, OF AMESBURY, MASSACHUSETTS, ASSIGNOR TO G. W. J. MURPHY COMPANY, OF AMESBURY, MASSACHUSETTS, A CORPORATION OF MASSACHUSETTS.

CHECK FOR DOORS.

Application filed May 3, 1924. Serial No. 710,854.

This invention relates to door checks or stops and the object is to provide a neat, durable and inexpensive device which may be applied to doors, particularly to the doors of vehicles with closed bodies to limit the opening movement thereof.

My invention will best be understood by reference to the following description of an illustrative embodiment thereof shown by way of example in the accompanying drawings, wherein:

Fig. 1 is a horizontal section through a portion of the hinge pillar of a vehicle body and the adjacent portion of the door, the door being in open position;

Fig. 2 is a similar view with the door closed;

Fig. 3 is a side elevation of the stop with the parts extended into alignment;

Fig. 4 is an inverted plan thereof; and Fig. 5 is a section on the line 5—5 of Fig. 4 on an enlarged scale.

My invention aims to provide a device to limit the opening movement of a door so that it will not swing open too far. For example, it will not swing through an angle of 180° and bang against the body of the vehicle on which it is mounted and mar the same. The construction takes the place of the strap or loop commonly used for this purpose on vehicle doors and provides a neater and more durable construction and also one which is exceedingly cheap to manufacture. The construction herein shown permits the door to open freely and to stand open if desired.

Referring particularly to Figs. 1 and 2 of the drawings, the stop may take the form of a series of hinge leaves 7, 9, 11 and 13, the leaves 9 and 11 being adapted to extend, as shown in Fig. 1, between points of the hinge pillar 15 and the hinge style 17 which separate from one another in the opening movement of the door and form a foldable connection adapted to lie between the pillar and style and be housed in suitable mortises therein when the door is shut, as shown in Fig. 2, and to open out and extend substantially diagonally across the angle therebetween when the door is swung open, as shown in Fig. 1. It will be obvious that as the leaves 9 and 11 come into alignment they serve as a connection across this angle between the door and the hinge pillar and prevent further swinging movement of the

door about its hinges 19. The leaves 7 and 13 provide convenient means for securing the ends of the leaves 9 and 11 to the door and to the hinge pillar, they being preferably attached by screws to the inner faces of the same, as shown in Figs. 1 and 2 of the drawing.

The hinge leaves 7, 9, 11 and 13 may conveniently be formed of flat strips of metal rolled to form hinge knuckles. As considerable strain may come upon the knuckles I preferably form the ends of the rolled portions (see Fig. 5) with tongues 21 adapted to extend through holes in the strips and be burred over as at 23 in the manner of rivets, thus providing in a convenient and inexpensive manner for very strong knuckles.

My invention particularly relates to means for preventing the toggle formed by the leaves 9 and 11 (see Fig. 1) from throwing over past dead center in order that it may always collapse and close between the door and the hinge pillar in the manner shown in Fig. 2 and further to means for minimizing the effect of the shock which is thrown on the stop by its action in halting the swinging movement of the door. For this purpose I provide suitable resilient means which will oppose the straightening out of the toggle and preferably this is arranged to come into action only when the links have nearly straightened out so that the door may open freely and may if desired stand open in the position of Fig. 1 without any tendency to reclose. To provide

for these functions I may rivet to leaf 11 a flat spring 25 having its end extending past the hinge joint between the leaves 9 and 11 and presented to the back of the leaf 9 so as to come in contact therewith and bear thereagainst when the leaves assume the position shown in Fig. 1 shortly before they come into alignment and to yield resiliently if the links are straightened out into alignment as shown in Fig. 3. It will be apparent that if the door is swung open counter-clockwise from the position shown in Fig. 2, the leaves 9 and 11 will first open freely without any resistance until substantially in the position of Fig. 1. The end of spring 25 then comes in contact with leaf 9 and is deflected by the further straightening movement of the toggle formed by the links 9 and 11. The limit of opening movement of

the door, as will be understood from Fig. 1, is reached when the links do come into alignment. In the latter part of this straightening action, therefore, the movement is cushioned and consequently a sharp shock is not thrown upon the parts particularly upon the knuckles and pintle connecting the leaves 9 and 11 which would tend to snap them. The reaction of the spring tends to return the leaves to the position shown in Fig. 1 slightly off dead center so that in closing movement of the door they collapse to the position shown in Fig. 2 in which position they are housed between the door and the hinge pillar. There is no danger of their breaking in the reverse direction so that they would project into the interior of the vehicle when the door was closed instead of returning to their inconspicuous housed position.

It will further be apparent that unless reverse breaking of the toggle were prevented the door might rebound and the tendency of the links folding in the other direction would be to draw it shut prematurely. In the embodiment of the invention shown this is prevented and because the spring 25 works only during a very short time as the door approaches its extreme open position the door may be opened freely and, while the sudden shock of stopping it is effectively cushioned, the leaves will be returned to the position shown in Fig. 1 somewhat off center in a position to fold up properly without there being any undue tendency through the reaction of the spring completely to reclose the door as in the case of spring hinges, commonly so-called, wherein opening movement is against the action of a spring.

I have described in detail the particular embodiment of my invention shown by way of example in the accompanying drawings. Obviously the details of mechanical construction may be considerably varied without departing from the spirit of the invention.

What I claim as new and desire to se-

cure by Letters Patent I shall express in the following claims.

1. A door stop comprising a pair of hinged leaves provided with means for connecting them to the hinge pillar and hinge style, said leaves adapted to fold between pillar and style when the door is closed and extend substantially diagonally therebetween when open and resilient means opposing the hinging of said leaves during the lattermost part of their opening movement only as they move toward alignment whereby to obviate sudden shock on the check as the door swings open.

2. A door stop comprising a pair of hinged leaves provided with means for connecting them to the hinge pillar and hinge style, said leaves adapted to fold between pillar and style when the door is closed and extend substantially diagonally therebetween when open and a flat spring secured to one leaf and having an end presented to engage the other during the lattermost part only of the opening movement of the leaves as they approach alignment.

3. A door stop comprising a pair of hinged leaves provided with means for connecting them to the hinge pillar and hinge style, said leaves adapted to fold between pillar and style when the door is closed and extend substantially diagonally therebetween when open and a spring stop which comes into action shortly before the leaves approach alignment to oppose further hinging movement of the leaves whereby to check sudden shock on the hinge and to prevent reversal of the same while leaving the door free to swing to and stand in open position.

4. A stop hinge comprising a pair of leaves pivoted together and a flat spring secured to one leaf having an end extending over the pivot and presented to engage the other leaf only shortly before the hinge reaches its desired maximum opening.

In testimony whereof, I have signed my name to this specification.

HERMENEGILDE CARRIER.
